Primary Examiner — Adir Aronovich(74) *Attorney, Agent, or Firm* — Haugen Law Firm PLLP(57) **CLAIM**

The ornamental design for a smartphone lens mount, as shown and described.

DESCRIPTION

FIG. 1 is a rear perspective view of a smartphone lens mount showing my new design;

FIG. 2 is a rear elevational view thereof;

FIG. 3 is a front elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines showing the interior of the lens apparatus and various screw components are for illustrative purposes only and form no part of the invention.
